Specification for Design.

Patented Apr. 13, 1920.

Application filed July 2, 1919. Serial No. 308,329. Term of patent 14 years.

To all whom it may concern:

Be it known that I, GUIDO G. BEHN, a citizen of the United States, residing at Detroit, in the county of Wayne and State of Michigan, have invented a new, original, and ornamental Design for a Radiator-Casing for Automobiles, of which the following is a specification, reference being had to the accompanying drawings, forming a part thereof.

Referring to the drawings, I have shown in Figure 1 a perspective view, and in Fig. 2 a front elevation of a casing of a radiator for automobiles embodying my new design.

What I claim is—

The ornamental design for a radiator casing for automobiles, as shown.

GUIDO G. BEHN.
